UNITED STATES PATENT OFFICE.

FRANK A. McGEE, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

BUCKLE.

1,245,749.

Specification of Letters Patent.

Patented Nov. 6, 1917.

Application filed May 5, 1916. Serial No. 95,528.

To all whom it may concern:

Be it known that I, FRANK A. McGEE, a citizen of the United States of America, and a resident of the city of Bridgeport, county 5 of Fairfield, and State of Connecticut, have invented a certain new and useful Improvement in Buckles, of which the following is a specification.

My invention relates to an improvement 10 in buckles and has particular application to a means for clamping the buckle to the tape or webbing. The object of the invention is to provide a superior and effective means of clamping as described, with the particular 15 advantages that the gripping or clamping member of the buckle extends from one side of the webbing to the other without injury thereto and without making any marks upon the webbing.

20 In the following I have described, in connection with the accompanying drawing, a means for carrying out my invention, the features thereof being more particularly pointed out hereinafter in the claims.

25 In the drawings, Figure 1 is a rear elevation of the buckle detached from the webbing with the lever in closed position;

Fig. 2 is a vertical sectional view of the same, strung with the webbing;

30 Fig. 3 is an end view of the same, strung with webbing as in Fig. 2, and showing, in dotted lines, the lever opened;

Fig. 4 is a rear elevation of the buckle detached from the webbing, parts being broken 35 away to show a modification of construction; and

Fig. 5 is a vertical sectional view of the form of device shown in Fig. 4.

Similar numerals of reference indicate 40 similar parts throughout the several views.

The loop is shown as constructed in the usual way and having an upper bar 1, a lower bar 2, side bars 3, 3 and a projecting finger piece 4, preferably integral with 45 lower bar 2 and lying in a plane at an angle to the plane of the loop.

The lever is shown as comprising a front plate 5, a back plate 6, extending at an acute angle to the front plate, and a portion bent 50 at 7 from the back plate toward the front plate, and then upward as at 8. In Figs. 1 to 3 inclusive, the back plate is shown as again bent or rolled rearwardly toward itself, as at 9, the substantially plane surface 55 of 9 forming a bearing for the upper bar 1

of the loop, said upper bar being confined between the portion 10 of the lever and said portion 9 thereof, the bent over portions of the back plate of the lever constituting an elongated spring cam, which when the lever 60 is closed clamps the running length 11 of the webbing 12 against the fixed end 13 of the webbing, folded over the lower bar 2 of the loop. It will be noticed that when the parts are in clamped position the inner bearing face of the bent over end of the back plate of the lever, as at 7, extends to the rearward of a line connecting the centers of the upper and lower bars. This assures 65 against accidental unclamping and assists in holding the parts firmly in clamped position. The webbing 12 may be slotted centrally to receive the finger piece 4, adapted to project through the slit, and thus hold or assist in holding, the fixed end of the web- 70 75bing, from displacement.

In Figs. 4 and 5 instead of rolling the portion 8 back against the back plate 6 of the lever, as shown at 9 in Fig. 2, the portion 8 is extended upwardly substantially 80 parallel to the back plate 6 until it contacts with the rear face of the front plate, sufficient space being left between the bottom of the portion 8 of the lever and the upper bar 1 of the loop for the reception of a wire 14, 85 which, like the portion 9 in Fig. 2, serves as a bearing for said upper bar 1 as shown. In this latter case also the bent over portions of the back plate form an elongated cam surface for clamping the running length of the 90 webbing as described.

In both forms the webbing is strung, preferably, by passing the slotted end of the webbing from rear to front over the lower bar of the loop and causing the finger piece projection 4 to enter the slit. The running length is then passed from front to rear over the fixed end and between the fixed end and the cam or clamp. By this means the buckle 95 is strung "rustless," and, when under tension, presents a substantially smooth back surface to the person of the wearer.

The buckle as described is easy to make, economical of material and efficient in action, while no injury or wear of the webbing 100 is suffered by the action of the clamp against it.

I do not restrict myself to the details as shown and described further than the scope of the appended claims demands.

I claim.

1. In a buckle, a loop member having an upper bar and a lower bar, and a lever member rotatably mounted on said upper bar, 5 said lever member comprising a front plate, and a back plate standing off from the front plate at an acute angle and receiving the upper bar of the loop in the angle and having its lower portion returned at an angle to- 10 ward the front plate and then bent upwardly in a plane substantially parallel with the back plate and adapted to form an elongated bearing for the lower face of the upper bar.
- 15 2. In a buckle, a loop member having an upper bar and a lower bar, and a lever member rotatably mounted on said upper bar, said lever member comprising a front plate, a back plate standing off from the front 20 plate at an acute angle and receiving the upper bar of the loop in the angle, and a portion bent toward the front plate from the back plate thence upwardly and thence re-
- 25 turned against the back plate, the upper face of the backwardly bent portion of the lever member being adapted to form an elongated bearing for the lower face of the upper bar and confine the said bar between itself and the angle.
- 30 3. In a buckle, a loop member having an upper bar and a lower bar, and a lever member rotatably mounted on said upper bar, the lever member comprising a front plate, a back plate bent at an angle to the front plate and a portion bent toward the front plate from the back plate, the inner bearing edge of the bent over portion of the back plate lying rearwardly of the plane through the centers of the upper and lower bars when the buckle is closed.

In testimony whereof I have signed this specification.

FRANK A. McGEE.
